UNITED STATES PATENT OFFICE.

HOWARD M. DUDLEY, OF PHILADELPHIA, PENNSYLVANIA.

DYEING-MACHINE.

1,275,878.

Specification of Letters Patent. Patented Aug. 13, 1918.

Application filed August 3, 1917. Serial No. 184,240.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to dyeing machines and refers particularly to those machines in which textile fibers are dyed under compression, the dye liquor being forced through the compressed mass.

The dyeing of fibers under these conditions presents many difficulties, as it is essential that all parts of the fiber mass be treated absolutely equally by the dye liquor, as otherwise uneven results will be obtained.

This equal treatment is dependent upon a number of conditions; the fiber must be uniformly and properly compressed, the liquor must be at a uniform pressure throughout the fiber mass, the formation of channels or passages within the fiber mass must be avoided, the dye liquor must be of such dilution as to prevent precipitation upon the fiber, the temperature of the liquor must be properly retained and means must be employed for determining the condition of the dyed fibers without interrupting the dyeing operation, opening the dyeing chamber or disturbing or sampling the fiber being dyed.

The device of my invention accomplishes all of the above results in a manner economical in construction and cheap, simple, accurate and positive in operation and possesses other advantages which will be evident upon a consideration of my specification, drawings and claims.

As a means for preserving uniform pressure throughout the fiber mass, preventing the formation of channels and causing an even and uniform distribution of the dye liquor, I inclose the compressed fiber between two foraminous plates, the plates being composed of parallel upwardly and downwardly extended members, having openings to allow of the passage of the liquor. In order to obtain a uniformly distributed pressure against the faces of the foraminous plates, I introduce a curved tubular liquid-supply member through which the liquid is forced, said liquid supply member having within

it a series of curved tubular members so shaped and arranged as to impinge the liquid equally and uniformly upon the faces of the plates.

In order to obtain a still further distribution of the liquid through the fiber mass, I employ means whereby the liquid may be passed through the mass in opposite directions as desired.

In order to judge of the condition of the fiber, I have a small dyeing device exactly similar and proportionate to the larger device and so constructed that fiber inserted therein will receive exactly the same treatment as that in the larger device, the same proportionate amount of the same liquor passing through both under the same pressure and temperature, so that in order to determine the condition of the dyeing, the operation in the large device need not be even interrupted, the large device need not be opened, and it will not be necessary to disturb the fiber contained therein.

I also employ means whereby the top of the dyeing receptacle may be readily removed to allow of the loading and unloading of the receptacle.

In the drawings, illustrating modified forms of the device of my invention, similar parts are designated by similar numerals.

Figure 1 is a cross-section of one form of my device.

Fig. 2 is a view looking in the direction of arrow 2 of Fig. 1.

Fig. 3 is a partial top-plan view of Fig. 1 with the top shown in its revolved position in dotted lines.

Fig. 4 is a cross-section through the line 4—4 of Fig. 1.

Fig. 5 is a broken enlarged cross-section of the testing device.

Fig. 6 is a top-plan view of one of the foraminous members of two of the foraminous plates.

Fig. 7 is a cross-section through the line 7—7 of Fig. 6.

Fig. 8 is a cross-section through the line 8—8 of Fig. 5.

Fig. 9 is a broken view looking in the direction of the arrow 9 of Fig. 5.

Fig. 10 is a cross-section through a modified form of a foraminous member of a foraminous plate.

Fig. 11 is a top-plan view of Fig. 10.

The device of my invention illustrated in the drawings, comprises a receptacle having the sides, 20, 21, 22, 23. The lower extremities of these sides are attached to the lower liquid-supply member 24 by means of the bolts 25, 25; and the upper extremities of the sides are attached to the upper liquid-supply member 26 by means of the bolts 27, 27. The lower liquid-supply member 24 has the valve 28 and is attached to the tubular member 29 by means of the bolts 30, 30. The member 29 carries the pipe 31 attached to the delivering pipe 32 of the pump 33. The receiving side of the pump 33 is connected to the pipe 34 which in turn is connected to the three-way pipe coupling 35. The pipe coupling 35 is connected to the pipe 36 connected to a source of liquid supply (not shown) and carrying the valve 37. The pipe coupling 35 is also connected to the pipe 38, having the valve 39, the other end of the pipe 38 being connected to the lower extremity of a liquid-supply tank 40. The upper liquid supply member 26 converges outwardly and then downwardly into the tubular member 41 carrying the valve 42, the member 41 entering the tubular member 29 and being connected thereto by means of the ball socket 43. The upper liquid supply member 26 contains a series of outwardly converging curved hollow members 44, 44, extending from the lower plane of the member 26 toward the smallest end of said member 26; and the lower liquid-supply member 24 contains a series of similar hollow members 45, 45.

Within the receptacle and extending across the same are a series of foraminous plates. Situated above the lower extremities of the sides 20, 21, 22, 23, is a foraminous plate 50 comprising a series of parallel serrated upwardly extended plates 51. Spaced above the foraminous plate 50 is a foraminous plate 52 comprised of a series of parallel members consisting of upwardly extended triangular members 53, 53, situated around circular openings 54, 54. Slidable within the receptacle is a foraminous plate 55 similar in construction to the plate 52, the triangular members 53, 53 extending downwardly. Spaced above the foraminous plate 55 is the foraminous plate 56 having a downwardly extended annular member 57, capable of abutment upon the upper surface of the plate 55. An angular annular member 58 is capable of abutment upon the upper face of the plate 56, and is capable of being moved downwardly within the receptacle and upon the plate 56 by means of the screw bolts 59, 59, threaded through the member 58 and the annular extension 60 of the sides of the receptacle. A pipe 61, carrying the valve 62 is connected with the receptacle above the plate 55 and opens into the upper portion of the liquid reserve tank 40. The

pipe 61 is connected with the pipe 63, having the valve 64, which in turn is connected with the receptacle below the plate 52.

A perforated steam pipe 70 is introduced into the receptacle.

The pump 33 is connected with the pipe 71 carrying the valve 72.

A conduit 80 connects the space between the foraminous plates 50 and 52 within the receptacle with the lower end of a testing device 81, the upper end of the testing device 81 being connected to the space between the foraminous plates 55 and 56 by the conduit 82. Extending with the conduits 80 and 82 are the pipes 85 and 86 having respectively the valves 83 and 84, close engagement between the conduits and the pipes being formed by the bushings 87, 87. The testing device 81 has annular members 88, 88 at each end thereof. Unions 89, 89 threaded upon the interior ends of pipes 85, 86 hold the testing device 81 in position. The testing device 81 contains foraminous plates and a fiber carrying chamber similar to those in the larger device.

In the foraminous member of the foraminous plate shown in Figs. 10 and 11, the extended members 53, 53 are situated around a rectangular opening 54, the foraminous plate comprising a series of such elements.

The operation of the device is as follows:

The top 26 is revolved into the position shown by the dotted lines 26^a of Fig. 3, thus opening the receptacle. The annular member 58 and the foraminous plates 56 and 55 are removed. The fiber 100 is then placed within the receptacle and upon the plate 52. The plates 55 and 56 and the member 58 are then introduced into the receptacle and pressed downwardly by means of the screw bolts 59, 59. The top 26 is then revolved over the top of the receptacle and clamped thereto by means of the screw bolts 27, 27. The testing device 81 is removed, packed with the fiber and replaced. All of the valves are closed with the exception of valves 37, 28, 62, 83 and 84. The pump 33 is then started, forcing the liquid from the supply tank (not shown) through the pipes 36, 34, 31, the curved tubular members 45, 45, the space 101, the foraminous plate 50, the space 102, the foraminous plate 52, the fiber 100, the foraminous plate 55, the space 103 and the pipe 61 into the liquid reserve tank 40. When sufficient liquid has been introduced, the valve 37 is closed and the valve 39 opened, thus allowing the liquid to flow from the tank 40 back into the pump 33 for continuous circulation. During this operation the liquid is also forced through the conduit 80, the testing device 81 and the conduit 82.

From time to time, as desired, the flow of the liquid is reversed by closing all of the valves with the exception of valves 42, 64

and 39, thus giving the liquid a downward circulation through the device.

When it is desired to wash the fiber, the dye liquor is removed from the device, the 5 valve 72 opened and fresh water delivered by means of the pipe 71 to the pump 33 from whence it is forced through the device.

When it is desired to determine the condition of the fiber 100, the valves 83, 84 are 10 closed, the testing device 81 removed and the contents examined, this operation being capable of performance without interrupting the operation of the larger device.

I do not limit myself to the particular 15 size, shape, number or arrangement of parts as shown and described, all of which may be varied without going beyond the scope of my invention as described and claimed.

What I claim is:—

20 1. In a dyeing machine, in combination, a receptacle having imperforate sides, two foraminous plates having extended members across the receptacle, openings between the extended members, means for maintaining 25 the plates at any position of separation with respect to each other, a fiber chamber between the plates and the sides of the receptacle, two foraminous plates spaced outwardly from the first two plates, and 30 means for forcing a liquid in opposite directions through the outer plate and then inwardly through the device.

2. In a dyeing machine, in combination, a receptacle having imperforate sides, two 35 foraminous plates within and extending across the receptacle, a fiber chamber between the plates and the sides of the receptacle, means for increasing and decreasing the size of the fiber chamber curved tubular 40 members above and below the receptacle and means for forcing a liquid in opposite directions through the curved members into and through the fiber chamber.

3. In a dyeing machine, in combination, 45 a receptacle having imperforate sides, two foraminous plates within the receptacle having extended convergent members, openings between the extended members, means for maintaining the plates at any position of 50 separation with respect to each other, a fiber chamber between the plates, curved tubular members above and below the foraminous plates and means for forcing a liquid through the tubular members, the plates and the fiber chamber in either direction.

4. In a dyeing machine, in combination, a receptacle having imperforate sides, two inner foraminous plates having extended members within the receptacle, openings between 60 the extended members, means for maintaining the two inner plates at any position of separation with respect to each other, two outer foraminous plates spaced respectively from the inner plates, curved tubular members respectively above and below the outer

plates, and means whereby a liquid may be forced through the tubular members, an outer plate, the space adjacent thereto, an inner plate and the fiber chamber in opposite directions through the device. 70

5. In a dyeing machine, in combination, a receptacle having imperforate sides, two inner foraminous plates having extended members within the receptacle, openings between the extended members, means for 75 maintaining the two inner plates at any position of separation with respect to each other, two outer foraminous plates spaced respectively from the two inner plates, a revoluble top to the receptacle, means for 80 permitting the revolution of said top to allow access to the interior of the receptacle, a series of curved tubular members within the top opening into the receptacle, a series of curved tubular members opening into the 85 bottom of the receptacle, a liquid supply tank, a pipe leading from above the upper inner plate to the liquid reserve tank, a pipe leading from below the lower inner plate to the liquid reserve tank, a pump, a pipe connecting the liquid reserve tank with the pump, and means whereby a liquid may be pumped in opposite directions through an outer foraminous plate, an inner foraminous plate, the fiber chamber and the liquid 90 reserve tank for continuous circulation. 95

6. In a dyeing machine, in combination, a receptacle having imperforate sides, two foraminous plates having extended members extending across the receptacle, openings between the extended members, means for maintaining the plates at any position of separation with respect to each other, a fiber chamber between the plates and the sides of the receptacle, two foraminous plates spaced 100 outwardly from the first two plates, a testing device exterior of the larger device, means whereby the contents of the testing device may be examined without interrupting the operation in the larger device, liquid 110 connecting means below the fiber chambers of the two devices, liquid connecting means above the fiber chambers of the two devices and means for passing a liquid through the two devices in opposite directions. 115

7. In a dyeing machine, in combination, a receptacle having imperforate sides, two foraminous plates within and extending across the receptacle, a fiber chamber between the plates and the sides of the receptacle, means for increasing and decreasing the size of the fiber chamber, curved tubular members above and below the receptacle and a testing device exterior of the larger device, means whereby the contents of the testing device may be examined without interrupting the operation in the larger device, liquid 120 connecting means below the fiber chambers of the two devices, liquid connecting means above the fiber chamber of the 125 testing device, liquid connecting means above the fiber chamber of the 130

two devices; and means for passing a liquid through the two devices in opposite directions.

8. In a dyeing machine, in combination, a receptacle having imperforate sides, two foraminous plates within the receptacle having extended convergent members, openings between the extended members, means for maintaining the plates at any position of separation with respect to each other, a fiber chamber between the plates, curved tubular members above and below the foraminous plates, a testing device exterior of the larger device, means whereby the contents of the testing device may be examined without interrupting the operation in the larger device, liquid connecting means below the fiber chambers of the two devices, liquid connecting means above the fiber chambers of the two devices and means for passing a liquid through the two devices in opposite directions.

9. In a dyeing machine, in combination,

a receptacle having imperforate sides, two inner foraminous plates having extended members within the receptacle, openings between the extended members, means for maintaining the two inner plates at any position of separation with respect to each other, two outer foraminous plates spaced respectively from the inner plates, curved tubular members respectively above and below the outer plates, a testing device exterior of the larger device, means whereby the contents of the testing device may be examined without interrupting the operation in the larger device, liquid connecting means below the fiber chamber of the two devices, liquid connecting means above the fiber chambers of the two devices and means for passing a liquid through the two devices in opposite directions.

Signed at New York in the county of New York and State of New York this 23rd day of July 1917.

HOWARD M. DUDLEY.
